UNITED STATES PATENT OFFICE

2,260,466

FASTENING-INSERTING MACHINE

John T. Lancaster, Newton, Mass., assignor to
 United Shoe Machinery Corporation, Borough
 of Flemington, N.J.

Application October 26, 1939, Serial No. 301,454

24 Claims. (Cl. 1-32)

My invention relates to machines for inserting fastenings in such work as shoes, it being of particular utility in connection with the attachment of heels.

In nailing heels to shoes, especially when the nails are driven from within a shoe, there is customarily employed a plurality of movable heel-engaging abutments, as one for the tread-end of the heel and one for the rear of said heel. It is important that the resistance of these abutments to displacement shall be correctly distributed and applied to ensure firm retention of the heel upon the heel-seat of the shoe, and, further, that the combined resistance offered by these abutments shall be at least as great as the thrust exerted by the nails as they are driven. To obtain this correct retentive effect is an object of my invention.

In the attainment of this object, as a feature of the invention, I utilize movable contact members for engagement with different heel-surfaces, as those at the tread-end and at the rear, and hydraulic pressure means having elements acting individually upon the members to effect their relative movement. This furnishes a simple and flexible arrangement by which the pressure, and under some conditions movement, may be transmitted from one member to another. The contact members may consist of a heel-tread-abutment and a rear abutment, there being connected to each of these a cylinder and a piston with hydraulic means for transmitting pressure between the cylinders and pistons of the abutments, as through a connecting pipe or conduit. By using a non-compressible liquid as the transmitting medium, a force created at one of the cylinder-piston-assemblies will impart a positive force to the other, and, by having pistons with different effective areas for the respective abutments, different forces may be applied to the work by said abutments. These abutments are best made variable in position to cause them to most effectively engage the work, and, to permit this, the hydraulic connection between the assemblies may be flexible. Preferably, there is means for delivering a liquid under pressure to the cylinders, and this pressure may be produced by the fastening-driving mechanism of the machine with which the work-pressing abutments are associated. There may be a work-support in which fastening-drivers are movable, a movable work-pressing head or carrier with a contact member or abutment movable upon it, and means, as a member operating under the power of the machine, for applying hydraulic pressure to the

drivers and contact member. Before the application of this final power-pressure, the head is locked or retained against movement. There are shown opposite members, which may consist of a cylinder and a piston, one having the drivers mounted upon it and the other being power-actuated, while a pipe or conduit joins the space between the members to the cylinder or cylinders of the pressure-head.

Another feature of the invention may be found in the work-engaging member of one of the abutments herein shown, as that for the rear of the heel. This engaging member is pivoted upon a support, and a spring is arranged to hold said member in its normal position and to allow it to yield in opposite directions. As herein disclosed, a yoke having heel-engaging means is trunnioned between spaced arms of the support, and the spring connects the yoke to the arms. With this arrangement, the pad or other means which engages the heel may rock upon contact therewith and adapt itself freely to that angle at which the rear of said heel may lie, and thus ensure effective retention.

In the accompanying drawings, a particular embodiment of the invention is illustrated,

Fig. 1 being a broken side elevation of a heel-attaching machine, in which my improvements are included;

Fig. 2, an enlarged broken side elevation of the pressure-head;

Fig. 3, a top plan view of the head with portions broken away;

Fig. 4, a front elevation of said head; and

Fig. 5, a top plan view of the abutment for the rear of the heel.

The general machine illustrated herein may be in many particulars that of Letters Patent of the United States No. 1,545,575, Standish, July 14, 1925, and as to this, a frame-column 10 has rising from a projection at its front a post 11, carrying upon it a work-supporting jack 12 adapted to receive upon its top a shoe S, to which a heel H is to be nailed. In passages in the jack-top, drivers 14 are arranged to be reciprocated by a plunger 16 movable in the post and upon which they are mounted. The plunger receives power, in a manner to be later explained, from a crank-pin 18 upon the forward extremity of a horizontal shaft 20 journaled in the column. A rear section of the shaft is driven, as from an electric motor, through gearing 22, rotation being communicated to the forward section 20 through clutch mechanism indicated at 24. Nails N, delivered to the jack-passages upon the ends

of the drivers by loading mechanism L, are inserted, upon the elevation of said drivers by the mechanism just indicated, through the heel-seat of the jacked shoe into the heel. Guided for vertical reciprocation upon the column 10 is a pressure-head or carrier 26, the elements which it bears holding the heel upon the heel-seat to resist the nail-inserting force. The head is held normally raised by a spring 28 acting through a lever 30 and is lowered to its work-engaging position by a rod 31 joining it to a treadle 32, which is fulcrumed yieldably at 34. After this engagement has occurred, the fulcrum of the treadle shifts to the rod 31, the rear of said treadle rises, and, through a link 36, causes the closure of the clutch 24. This revolves the crank-pin 18 to raise the drivers 14 for the insertion of the nails. At the same time, the head 26 is locked by interleaved clutch-plates 38 forced together, as in the previously mentioned patent, by connections 40 actuated by a cam 42 fast upon the shaft 20. In the present instance, however, the lower set of plates is not bodily movable, but is fixed upon a bracket 44 secured to the column 10. Consequently, the clutch device serves to hold the head temporarily against movement. Considering the details of my improved heel-engaging mechanism carried by the head 26, this head has formed at its opposite sides horizontal ways 50, 50 (Fig. 4). In these ways are movable a forward slide 52 and a rear slide 54 (Fig. 3). Rotatable at opposite sides of the top of the head are horizontal rods 56 and 58. The rod 56 is threaded through a lug 60 projecting upwardly and outwardly from the slide 52, while the opposite rod 58 similarly engages a lug at one side of a boss 62 upon the slide 54. By rotating the rods, the two slides, and the elements which they carry, are adjusted in position from front to rear of the machine in the desired relation to the jacked work and there held. Hand-wheels 64 secured to the forward extremities of the rods facilitate the adjustments. Depending from the slide 52 is a bracket 66, upon which is pivoted at 68 a cylinder 70 having movable in it a piston 72. The lower extremity of the piston has at 74 a surface adapted for contact with the tread-end of a heel positioned upon a jacked shoe. The angle of the cylinder and piston may be varied by tilting them about the pivot 68. This may be effected by a rod 76 linked to the cylinder at 78 and passing through a lug 80 upon the bracket. Rotatable in the lug is a hand-nut 82, through which the rod 76 is threaded. By turning this nut, such an angular adjustment may be made that the piston 72 will be correctly aligned with heels of different pitches. With the slide 54, a vertical cylinder 84 is shown as formed, and in this cylinder a piston 86 is arranged to reciprocate, this piston furnishing a support for an abutment A for engagement with the rear of the heel. At the lower extremity of the piston is a fork having spaced arms 88, 88 (Fig. 5), in which is trunnioned at 90 a yoke 92. At the center of the yoke, approximating in form the curvature of the rear of the heels to be attached, is a depression, and over this depression a pad 94, of some such yieldable material as leather, is attached to prevent marring the heel-coverings. The yoke and its pad are held in a normal position, so the surface of the pad approximates the heels in inclination, by a tension-spring 96 stretched between the arms of the supporting piston and passing through a horizontal depression at the rear of the yoke. As heels with their

varying pitches depart from this normal inclination of the pad, the spring permits the yoke to yield, either up or down, for the most perfect contact with the rear heel-walls. To maintain the rear abutment against turning about the axis of the piston 86, there is an upward projection 98 from the rear of the arms 88, 88, this having an inner face moving over a flattened surface upon the outer wall of the cylinder 84. The abutment A is held normally in an elevated position by a tension spring 100 joining the rear of the fork to the slide 54. The cylinders 70 and 84 of the tread-abutment and the rear abutment are hydraulically connected, so the movement of one compels a like but opposite movement of the other. Threaded into the top of the cylinder 70 and into the boss 62, which has a vertical passage communicating with the cylinder 84, are nipples 102, 102, having means to clamp in place the opposite ends of an upwardly curved section of flexible pipe 104, providing a conduit connecting the cylinders. A contained liquid, such as glycerin or oil, may thus flow into and out of either cylinder. Assuming the space furnished by the cylinders and pipe to be otherwise closed, when the rear abutment is raised by its spring the tread-abutment will be lowered by the pressure transmitted from the piston 86 by the liquid to the piston 72. Since the liquid is non-compressible, the force thus applied will be positive. When the tread-abutment is raised, the rear abutment will, in a like manner by the hydraulic compensating connections, be positively lowered, the two accommodating themselves perfectly to varying heights and forms of heels. It may be desired to apply greater pressure to the heel by one abutment than the other. This being the case, the areas of the ends of the pistons are made different. Usually, the piston of the rear abutment would have the larger area, holding the heel firmly against being forced back by the horizontal component of the clamping force produced by the pitch. At the highest point of the pipe 104, a fitting 106 is included, at the top of which is an opening closed by a screw-plug 108. Through this opening liquid may be introduced to fill the connected spaces. To prevent the liquid from dripping from the cylinders, the pistons are surrounded by the usual expandable rings 110, and below these may be scavenging grooves 112 from which passages 114 lead into spaces within the pistons. Screw-plugs 116 close the spaces at the top, while at the bottom are screw-plugs 118 which, when removed, allow the accumulated liquid to be emptied from the spaces. The hydraulic system is preferably utilized to more exactly obtain a final clamping pressure upon the heel, which will ensure retention against displacement of the work from the jack, by the lifting force of the nails as they are driven. The lower portion of the driver-plunger 16 is in the form of a tubular piston 128, movable within a cylinder 130 guided for reciprocation in the post 11. The cylinder is joined at its lower extremity to the crank-pin 18 by a connecting rod 132. The weight of the piston and the driver-assembly is borne upon a helical spring 134 interposed between it and the bottom of the cylinder. The upward movement of the piston under the influence of the spring is limited by a screw 136, threaded through the cylinder-wall and having at its inner extremity contact with the bottom of a slot 138 surrounding the piston. This slot

is wider than the end of the screw, so there is a capacity for relative vertical movement between the piston and cylinder. Into an opening in the wall of the cylinder, a nipple 140 is made, and to this is clamped the lower extremity of a flexible pipe or conduit 142, the upper end of which communicates with a passage 144 formed in the slide 54 and opening into the cylinder 84 of the rear heel-abutment. There is thus a space between the piston 128 and cylinder 130 and in the connections joined to the cylinders 84 and 70 and the pipe 104 to form therewith a common chamber, which is completely filled with the liquid already referred to. To permit the full entry of liquid into the chamber, the space in the piston 128 is continued through the plunger 16 by a passage 146 and is normally closed by a screw-plug 148. When the liquid is introduced through the opening at 108, this plug 148 is temporarily removed to vent the chamber. The usual rings 150 surrounding the piston 128 prevent leakage.

With the pressure-head 26 elevated by the spring 28, the operator adjusts, if necessary, the horizontal relation of the tread-abutment 72, 74 and the rear abutment A by the hand-wheels 64 and the angle of the tread-abutment by the nut 82. He then applies a shoe S to the jack 12, places a heel H upon the heel-seat and depresses the treadle 32. This first, through the rod 31, lowers the head until the surface 74 engages the tread-end of the heel. The piston 72 yields, and through the connecting body of liquid the companion piston 86 is lowered against the supporting force of the spring 100 until the pad 94 contacts with the rear of the heel and adjusts itself angularly by virtue of the yield of its spring 96. The two abutments are now bearing upon the heel, though the force exerted by the rear pad will exceed that of the tread-surface 74 because of the greater area of the end of the piston 86. Further depression of the treadle by the operator transfers its fulcrum from the pivot 34 to the connection with the rod 31, raising the link 36 to trip the clutch 24. This causes the performance of a power-cycle of the machine. The head 26 is at once locked to the frame by the plates 38 clamped together by the cam 42, to hold upon the work treadle-created preliminary pressure of the rear and tread-abutments. Revolution of the crank-pin 18 elevates the cylinder 130. The non-compressible body of liquid between the cylinder and the piston 128 lifts the latter positively to insert the nails N, which have been previously delivered upon the drivers 14 by the loader L, through the heel-seat of the shoe into the heel. As the entrance of the nails into the work is resisted, the pressure created by the reaction is transmitted by the liquid through the pipe 142 and the connections to the abutment-cylinders 70 and 84. The effective areas of the opposed surfaces of the piston 128 and the cylinder 130 are at least as great as the combined surfaces of the ends of the abutment-pistons 72 and 86. Consequently, there is applied to the work a final clamping pressure by which it is unfailingly held against being forced upwardly from the jack-top by the entering nails, and the heads of said nails will be fully seated in the insole. To whatever extent the work is compressed, the hydraulic pressure will also produce movement of the pistons 72 and 86, so their abutments will follow this compression. This causes relative movement between the piston 128 and the cylinder 130, which is permitted by the clearance between the cyl-

inder-projection 136 and the wall of the piston-groove 138. At the termination of the cycle, the crank-pin 18 lowers the cylinder 130, and therefore the drivers 14. The hydraulic pressure applied through the pipe 142 to the rear and tread-abutments is relieved to remove the clamping pressure. The cam 42 releases the plates 38, so the spring 28 lifts the head 26 to the normal position. The spring 100 raises the rear abutment A and hydraulic pressure transmitted through the pipe 104 lowers the tread-abutment upon the piston 72. The heeled shoe may now be removed from the jack.

Having described my invention, what I claim is new and desire to secure by Letters Patent of the United States is:

1. Heel-pressure mechanism comprising movable contact members for engagement with different heel-surfaces, and hydraulic means having elements respectively individual to the members and acting thereon to effect their relative movement.

2. Heel-pressure mechanism comprising a movable carrier, contact members movable upon the carrier for engagement with different heel-surfaces, means for retaining the carrier against movement, and means made effective after the retention of the carrier for applying pressure to the contact members.

3. Heel-pressure mechanism comprising a movable carrier, contact members movable upon the carrier for engagement with different heel-surfaces, means for retaining the carrier against movement, and hydraulic means for applying pressure to the contact members.

4. Heel-pressure mechanism comprising a tread-abutment, a rear abutment, a cylinder and piston connected to each abutment, and hydraulic means for transmitting pressure between the cylinders and pistons of the abutments.

5. Heel-pressure mechanism comprising a tread-abutment, a rear abutment, a cylinder and piston connected to each abutment, such pistons having different effective areas, and hydraulic means for transmitting pressure between the cylinders and pistons of the abutments.

6. Heel-pressure mechanism comprising a tread-abutment, a rear abutment, a cylinder and piston connected to each abutment, a conduit joining the cylinders, and means arranged to supply liquid to the cylinders and conduit.

7. Heel-pressure mechanism comprising a carrier, two cylinders mounted upon the carrier, a piston movable in each cylinder, a heel-contact member carried by each piston, and means for delivering liquid under pressure to the cylinders.

8. Heel-pressure mechanism comprising a movable carrier, two cylinders mounted upon the carrier, a piston movable in each cylinder, a heel-contact member carried by each piston, means for locking the carrier against movement, and means made effective after the locking of the carrier for delivering liquid under pressure to the cylinders.

9. Heel-pressure mechanism comprising a carrier, two cylinders mounted upon the carrier, a piston movable in each cylinder, a heel-contact member carried by each piston, and a pipe joining the cylinders.

10. Heel-pressure mechanism comprising a carrier, a cylinder mounted upon the carrier, a cylinder variable in position upon the carrier, a piston movable in each cylinder, and a heel-contact member carried by each piston, the cylinders be-

ing connected and arranged to contain a body of liquid between the pistons.

11. Heel-pressure mechanism comprising a carrier, a cylinder mounted upon the carrier, a cylinder variable in position upon the carrier, a piston movable in each cylinder, a heel-contact member carried by each piston, and a flexible pipe joining the cylinders.

12. Heel-pressure mechanism comprising a carrier, two slides movable upon the carrier, a cylinder mounted upon one slide, a cylinder movable upon the other slide, a pipe connecting the cylinders, a piston movable in each cylinder, a heel-contact member carried by each piston, means arranged to move the slides upon the carrier, and means arranged to shift the movable cylinder upon its slide.

13. Heel-pressure mechanism comprising a carrier, two slides movable upon the carrier, a cylinder mounted upon one slide, a cylinder pivoted upon the other slide, a pipe connecting the cylinders, a piston movable in each cylinder, a heel-contact member carried by each piston, means arranged to move the slides upon the carrier, and means arranged to vary the angle of the pivoted cylinder upon its slide.

14. In a fastening-inserting machine, a work-support, fastening-drivers movable therein, a work-pressing head co-operating with the work-support, a work-contact member movable in the head, and means connected to the support and head for applying fluid-pressure to the drivers and to the contact member.

15. In a fastening-inserting machine, a work-support, fastening-drivers movable therein, a movable work-pressing head co-operating with the work-support, means for locking the head against movement, a work-contact member movable in the head, and means connected to the support and head for applying fluid-pressure to the drivers and to the contact member.

16. In a fastening-inserting machine, a work-support, fastening-drivers movable therein, a work-pressing head co-operating with the work-support, opposite members movable in the work-support upon one of which members the drivers are mounted, means for reciprocating the other member, a cylinder and piston relatively movable in the head, a work-contact member movable by said cylinder and piston, and a conduit joining the space between the members in the support to the cylinder.

17. In a fastening-inserting machine, a work-support, fastening-drivers movable therein, a work-pressing head co-operating with the work-support, a cylinder movable in the support, a piston movable in the cylinder and upon which the drivers are mounted, means for reciprocating the cylinder, a cylinder mounted upon the head, a piston movable in the cylinder, a work-contact

member carried by the piston, and a pipe connecting the cylinders.

18. In a heel-attaching machine, a jack, a cylinder movable in the jack, a piston movable in the cylinder, drivers reciprocated by the piston in the jack, means for reciprocating the cylinder, a pressure-head co-operating with the jack, cylinders mounted upon the head, pistons movable in the cylinders, a heel-tread-abutment and a rear abutment carried by the head-pistons, and pipes connecting the jack-cylinder and the head-cylinders.

19. In a heel-attaching machine, a jack, a cylinder movable in the jack, a piston movable in the cylinder, drivers reciprocated by the piston in the jack, means for reciprocating the cylinder, a pressure-head co-operating with the jack, cylinders mounted upon the head, pistons movable in the head-cylinders and having a combined effective area at least as great as that of the jack-piston, a heel-tread-abutment and a rear abutment carried by the head-pistons, and pipes connecting the jack-cylinder and the head-cylinders.

20. In a heel-attaching machine, a jack, a cylinder movable in the jack, a piston movable in the cylinder, drivers reciprocated by the piston in the jack, means for reciprocating the cylinder, a pressure-head co-operating with the jack, cylinders mounted upon the head, means arranged to move the head-cylinders toward and from each other upon the head, means arranged to vary the angle of one of the head-cylinders, pistons movable in the head-cylinders, a heel-tread-abutment and a rear abutment carried by the head-pistons, and pipes connecting the jack-cylinder and the head-cylinders.

21. In a heel-attaching machine, a heel-abutment comprising a support, a heel-engaging member pivoted upon the support and yieldable in either of opposite directions at all times under the influence of the work, and a spring arranged to hold the heel-engaging member in a normal position and to allow its yield.

22. In a heel-attaching machine, a heel-abutment comprising a support provided with spaced arms, a yoke trunnioned between the arms for engagement with the rear of a heel, and a spring connecting the yoke to the support.

23. In a heel-attaching machine, a heel-abutment comprising a support provided with spaced arms, a yoke trunnioned between the arms and having a heel-engaging pad, and a spring connecting the yoke to both arms of the support.

24. In a heel-attaching machine, a pressure-head, a slide movable thereon and having spaced arms, a yoke trunnioned between the arms for engagement with the rear of a heel, and a spring connecting the arms and being under tension, said spring acting at its center upon the yoke.

JOHN T. LANCASTER.
